UNITED STATES PATENT OFFICE.

WILLIAM ARTHUR LEE, OF WICHITA, KANSAS.

TRAFFIC SIGNAL.

Application filed August 8, 1921. Serial No. 490,652.

To all whom it may concern:

Be it known that I, WILLIAM ARTHUR LEE, a citizen of the United States, residing at Wichita, in the county of Sedgwick and State of Kansas, have invented new and useful Improvements in Traffic Signals, of which the following is a specification.

This invention relates to a traffic signal particularly designed for use upon motor vehicles and an object of the invention is to provide a traffic signal that may be mounted on any vehicle and give a distinct signal from one side of the vehicle as to the direction it is about to take which signal can be distinguished night or day and under all weather conditions.

Another object of this invention is to provide a signal as specified which may be used upon closed cars, one with which the use of side curtains will not in any way interfere, as well as one which is operated by a relatively small lever located in close proximity to the steering wheel of the vehicle and which requires little effort to operate, and one which latches itself in adjusted position and remains there until it is changed by the operator.

Another object of the invention is to provide a signal as specified which includes a movable semaphore arm carrying visible signals in the form of a plurality of lights to clearly indicate the direction to be taken by the vehicle and which signal mechanism further embodies a structure for automatically cutting off the energizing or exciting of the lamps or lights when the semaphore arm is moved or dropped into neutral position.

It has been determined by observation that drivers of closed motor vehicles or motor vehicles with side curtains in place seldom give a signal when turning and it is a well known fact that especially during rainy weather or cold or damp weather that signals are more necessary than at any other time owing to the danger of skidding and it is an object of this invention to provide a signal mechanism which may be conveniently operated from the interior of the car eliminating the necessity of the driver of extending his arm out of the car during cold or rainy weather.

Other objects of the invention will appear in the following detailed description and in the accompanying drawings wherein:

Fig. 1 is a side elevation of the improved traffic signal.

Fig. 2 is a fragmentary top plan of the traffic signal.

Fig. 3 is a fragmentary edge elevation of 60 the semaphore arm.

Fig. 4 is a fragmentary view, partly in section and partly in side elevation, showing the operating lever.

Fig. 5 is a section on the line 5—5 of 65 Fig. 3.

Fig. 6 is a section on the line 6—6 of Fig. 1.

Fig. 7 is a section on the line 7—7 of 70 Fig. 1.

Fig. 8 is a plan of a bracket used in attaching the signal to a closed car.

Fig. 9 is a side elevation of the bracket illustrated in Fig. 8.

Referring more particularly to the drawing the improved traffic signal includes a semaphore arm 1 which comprises a tube 2 which has a head 3 mounted upon its outer end and an elbow member 4 upon its inner end. The head 3 is constructed of suitable sheet metal and its sides 5 and 6 are perforated providing suitable openings arranged in pairs one directly opposite the other as clearly shown in Fig. 7 of the drawing through which openings lenses protrude. The lenses 7 which protrude through the openings in the sides 5 and 6 nearest the inner end of the head 3 are larger than the lenses 8, so as to provide a diminishing stream of light outwardly from the pivot of the semaphore arm to indicate the direction in which the arm is pointing. The gaskets 9 are placed within the head 3, the lenses 7 engaging against these gaskets being secured in place in any suitable manner. Incandescent electric lamp bulbs 10 and 11 are positioned between each pair of lenses 7 and 8 to illuminate the lenses and render the head 3 clearly visible. The bulbs 10 and 11 are carried by a double socket structure 12 which is similar to the construction of sockets used in motor vehicle constructions differing only in that it is double so as to permit the supporting of the bulbs 10 and 11 at its opposite ends and also to permit synchronous exciting of the bulbs 10 and 11. The current is supplied to the socket structure 12 through the usual central core 13 into which a binding screw 14 is threaded, intermediate the ends of the socket and to 90

which binding screw the electric current conducting wire 15 is connected. The outer shell 16 of the socket structure 12 is grounded in the usual manner. The wire 15 extends longitudinally through the tube 1 and has its end, remote from the binding screw 14, attached, in any suitable manner as at 17, to the stem 18 of a cap member 19. The cap member 19 is slidably supported within a cylinder 20 formed of electrical conducting material which cylinder is in turn slidably supported by an insulating sleeve 21 through which the stem 18 extends and to which said stem is connected. A spiral spring 22 is positioned within the contact sleeve 20 and extends into the cap 19 for urging the sleeve 20 outwardly, the outward movement of the sleeve being limited by the turned flange 23 on its inner end. The insulating sleeve 21 extends into a metal sleeve 24 which is held against movement by means of a suitable screw 25. The contact sleeve 20 is urged by the spring 22 into engagement with the perimeter of the circuit maker and breaker structure 26 which is mounted upon the shaft 27. The shaft 27 is in turn carried by the bracket body 28, which is supported from the vehicle body preferably from the wind-shield structure part of which is indicated at A, by means of a clamping bracket structure 29. The clamping bracket structure 29 comprises jaws 30 which are clamped to the wind-shield A by any suitable means as indicated at 31. The circuit maker and breaker structure comprises a sleeve 32 of suitable insulating material which has a metal band 33 mounted upon its perimeter. The band 33 extends about substantially two-thirds of the perimeter of the insulating sleeve 32 and the strip 34 of metal is attached to the sleeve 32 and extends over the major portion of the perimeter of the sleeve, which is not enclosed by the band 33, however, spaces, as shown at 35, are left between the facing ends of the band 33 and strip 34 so that the strip 34 will be insulated from the band 33. The band 33 has an ear 37 thereon to which an electrical conducting wire 38 is connected by means of a suitable binding screw 39. The elbow 4 has its arm 40 mounted upon the stub shaft 27 and an extension 41 is formed on the arm 40 to increase the bearing surface of the arm with the shaft 27. A suitable insulating sleeve 42 is mounted about the extension 41 and extends into the insulating sleeve 32 as clearly shown in Fig. 6 of the drawing. The elbow 4 has an arm 44 formed thereon to which a link 45 is connected. The link 45 is connected to a wire or flexible rod 46 which projects through the flexible shaft structure 47. The flexible shaft 47 is connected to the bracket 28 by means of a socket 49 as clearly shown in Fig. 1 of the drawing, and it is also connected to a quadrant 50 which is clamped to the steering post B of a vehicle by means of a clamp structure 51. The wire 46, which extends through the flexible shaft structure 47, is connected, as shown at 53, to a lever 54 pivotally carried by the quadrant 50 so that when the lever 54 is operated the semaphore arm 1 will be moved upon the shaft 27 as a pivot to indicate the direction about to be taken by the vehicle upon which the improved traffic signal is mounted. A dog 56 is pivotally carried by the lever 54 and has a rod 57 connected thereto which extends centrally through the handle 58 having a head 59 thereon which is mounted in a sleeve 60. A spiral spring 61 is mounted in the sleeve 60 and engages the head 59 for urging the head upwardly and consequently urging the dog 56 into engagement with one of the notches 62 in the quadrant 50. A button head 63 projects through the end of the handle 58 to permit compressing of the spring 61 for rocking the dog 56 to release its engagement with the quadrant 50 and allow the lever 54 to be rocked for rocking the semaphore arm 1. The quadrant 50 is provided with a plurality of notches 62, one being provided for the neutral position of the semaphore arm, one for positioning of the semaphore arm at a downward incline of substantially 45 degrees, one for holding the semaphore arm in horizontal position, and a fourth one for holding the semaphore arm in upwardly inclining position, which positions are universally known to represent different directions in which a car is to be moved, and also a suitable notch adapted to receive the dog or pawl 56 to support the semaphore arm in an upright position to indicate that the driver of the vehicle is about to back the same. When the semaphore arm 1 is in neutral position or in other words is hanging downwardly the contact sleeve 20 is in engagement with the strip 34 which prevents the passage of energizing current to the lamp bulbs 10 and 11, however, when the semaphore arm is released into any position above its downwardly extending vertical position the contact 20 will be brought into engagement with the band 33 which will close and excite or energize a circuit through the bulbs 10 and 11 causing them to light so that the light rays therefrom will pass through the lenses 7 and 8 to clearly indicate the direction in which the arm is extended even at night. A cushion 66 is carried by the head 3 to prevent the marring of the vehicle body and the flexible shaft 47 is enclosed in a suitable leather casing 67 to prevent marring of the vehicle body. In Figures 8 and 9 a bracket structure 70 is shown which is provided for attachment to a closed body of a motor vehicle such as a sedan, coupé, or the like, the said bracket

replacing the clamp structure 29 and comprising an attaching portion 71 and a carrying arm 72 the outer end of which is flattened to provide an eye 73 which is connected to the bracket 28 by means of the bolt and nut 74 and 75 shown in Fig. 1 of the drawing.

From the foregoing description taken in connection with the accompanying drawing it will be apparent that a traffic signal has been provided which is comparatively simple in construction which may be conveniently operated and one which will enable a driver following a vehicle to determine the exact direction about to be taken by the preceding vehicle and the signal structure which can be seen both from the front and rear of the vehicle carrying same owing to the provision of the lenses.

It is, of course to be understood that the invention may be constructed in various other manners and the parts associated in different relations and, therefore, I do not desire to be limited in any manner except as set forth in the claim hereunto appended.

Having thus described my invention what I claim is:

In a traffic signal, a supporting bracket, a shaft carried by said supporting bracket, a semaphore arm pivotally supported by said shaft and having electrically operating signalling means carried thereby, a hollow elbow at the inner end of said arm, a supporting sleeve in the outer end of said elbow, an insulating sleeve in said supporting sleeve, an electric terminal in the insulating sleeve, a movable cylinder having contact with the terminal, an insulating sleeve mounted upon said shaft, a contact band extending partly around the perimeter of said last insulating sleeve, a metal strip attached to the perimeter of the metal sleeve on the shaft other than the portion enclosed by the contact band, said metal strip and contact band having their ends spaced and a coil spring within the cylinder for urging the same into engagement with the contact band or metal strip.

In testimony whereof I affix my signature.

WILLIAM ARTHUR LEE.
